The leading feature of my design, which relates to nails or slugs for ornamenting boot or shoe heels, consists in the V-shaped outwardly-turned longitudinal grooves in opposite sides of a nail or slug, forming a thin connection between two larger portions square 15 in cross-section.

The nail or slug has formed in its opposite sides longitudinal V-shaped grooves e with 20 the open or wide part of the grooves turned outwardly, forming a thin connection e' between the two larger portions e^2 , which are square in cross-section.

I claim—

The design for a nail or slug substantially 25 as set forth.

In testimony whereof I have signed my name to this specification in the presence of two subscribing witnesses.
